(57) **CLAIM**

We claim the ornamental design for a detergent container for washing machine, as shown and described.

DESCRIPTION

FIG. 1 is a front perspective view of a detergent container for washing machine showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an exploded view of the detergent container for washing machine in which the upper right portion is shown separated from the body of the detergent container for washing machine;

FIG. 9 is an exploded view of the detergent container for washing machine in which the upper left portion is shown separated from the body of the detergent container for washing machine; and,

FIG. 10 is another front perspective of the detergent container for washing machine in which the body of the washing machine is provided in broken lines to illustrate an example environment.

The broken lines in the figures show portions of the detergent container for washing machine which form no part of the claimed design.

The dot-dash broken lines in the figures represent an unclaimed boundary line and form no part of the claimed design.
